MUSIC PRINTING DEVICE

Edward J. Clark, Bethayres, Pa., assignor to International Business Machines Corporation, New York, N. Y., a corporation of New York

Application June 28, 1947, Serial No. 757,862

31 Claims. (Cl. 84—462)

1

The present invention relates in general to music recording devices and more particularly to apparatus for printing a musical composition as it is being originated by a composer playing a piano or other musical instrument having operating instrumentalities.

The invention relates further to musical composition writing apparatus for making a permanent record of an original musical composition on music staff paper or paper ruled to receive musical notes so that the music may be read directly from such original impressions or so that it may be readily transcribed with additional notation according to the conventional system of music writing.

An object of the invention is to provide devices for recording actual note shapes in their proper position with relation to staff lines and with sharp and flat notations directly controlled by the musical instrument.

One of the objects of the invention is to provide an automatic apparatus which is controlled by the keyboard or operating instrumentalities of a musical instrument such as piano, organ, trumpet, etc., whereby the depression of each key energizes electromechanical circuits connected to corresponding note marking members disposed in operative relation to a strip of note paper propelled at a predetermined speed according to the selected tempo of the music to be played. As an alternative to the recording by mechanical means, it is provided herein that the depression or actuation of each operating instrumentality may cause the flashing of a masked light to record photographically the various note shapes on a photosensitive paper arranged with the staff lines and propelled for various tempos.

An object of the invention is to provide photographic means for recording actual note shapes of a plurality of different time values directly from the instrument as played.

A further object of the invention is to provide music recording means to enable a composer to obtain a permanent and readable record of any original musical composition as it is being played on a musical instrument without any need for interrupting the playing. A feature of the device is that automatic controls dispense with the need of attention on the part of the composer. Music recording is generally done by hand step by step by the composer when he plays a chord or two and then stops the composition to write down the particular chord as closely as he is able to remember it. This procedure is repeated with the continuous interruptions having bad effect on the con-

2

tinuity of his work. Often the composer finds it necessary to employ someone capable of transcribing and copying the composition as it seems to impress him. This is a procedure which is tedious, inaccurate and expensive and which can be eliminated by the use of the device of the present invention.

An object of the invention is to provide recording means adaptable for continuous automatic and rapid recording to avoid intermittent and slow manual recording systems, whereby the composer may work continuously and rapidly, devoting his entire attention to the artistic work rather than the mechanisms of manually recording the composition.

The devices shown comprise electrical contact means extending over and under the operating instrumentalities of a musical instrument to control not only according to the particular instrumentality operated but also according to the time of operation as related to the time of operation of other instrumentalities and also according to the time during which any instrumentality is held operated. Each electrical contact device is connected to a photographic or electromechanical recording device arranged in proper position across the width of a moving band of plain or sensitized note film or paper, which is in continuous and uniform motion, whereby the operation of any instrumentality will be caused to make a permanent note shape upon the paper in the proper spaced relationship to the staff lines to denote the proper tone quality according to the instrumentality operated. Operating in synchronism with the motion of the recording strip is an electrical commutator or timer for selecting in any of the note positions a particular one of several time value note shapes, for example, the $\frac{1}{16}$, $\frac{1}{8}$, $\frac{1}{4}$, $\frac{1}{2}$, $\frac{3}{4}$, and whole note shapes are selected in the order mentioned according to the time of depression of the related musical operating instrumentality.

Therefore, when a composer operates a key, the recording devices not only serve to select the tone values that he selects but also the time relationship that he selects for the particular note with relation to other notes selected with, before and after the particular note recorded.

Another object of the invention is to provide means for not only varying the speed of movement of any musical recording sheet according to various tempos but also coordinate and synchronize therewith an electrical commutator or timer for determining the time values of various notes which are recorded accurately to represent

the actual sustaining time selected by the composer for the variable tempos.

Another object of the invention is the provision of means whereby the sharp and flat notations may be recorded wherever necessary by the relative positioning of photographic or electromechanical pairs of recording means adjacent to proper natural note recording members. As in the example shown, operation of the black keys of the piano cause operation of extra contact devices related to the two adjacent white keys, so that either of the white key notations may be recorded along with the recording of a sharp or flat notation.

Another object of the invention is the provision of means for automatically selecting a recording of either sharps or flats according to the wishes of the composer. A pair of pedals are provided to be operated by a foot of the composer to select the sharp and flat notation. Electrical circuits are provided for automatically selecting either sharp or flat notation selectively and dispense with the other selection made by the same key. The same sort of selection is made for each key separately when the pedals or levers are multiplied so that there is one pair for each black key.

An object of the invention is to provide improved means whereby each beat will be audibly indicated to the composer and whereby the first beat of every count will also be audibly and visibly indicated and with contrasting sound, so that the musician may perform in correct time relation to the particular speed or tempo and movement of the note sheet for which the recording machine is set. An operating panel is provided for observation at the instrument, whereupon the selected tempo may be noted and adjusted and whereupon the visual recording by a flashing light indicates the first beat of every count or bar line of every measure.

The beat of the recording apparatus may be changed from time to time to correspond to various tempos such as presto, allegro, adagio, largo and lento.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a diagrammatic sectional elevation view of the music note print recorder showing representative piano key contacts and control circuits.

Fig. 2 shows a sample length of music strip, sheet or film upon which the notes and signs are recorded.

Fig. 3 is a sectional view of the sheet of a plural layered variety.

Fig. 4 is a diagrammatic showing of the location of the sharp and flat recorders with respect to the staff lines on the recording sheet or film.

Fig. 5 is a plan view of the recorder, a few representative keys and the pedals for controlling the recording of either sharps or flat. This view also shows an alternative kind of recording for making photographic exposures of the music note shapes on film.

Fig. 6 is a plan view of a photographic shutter in one of the recording cells or boxes of the recorder.

Fig. 7 shows one of the photographic masks or shields which is situated at the bottom of a photographic recording cell.

Fig. 8 is a sectional elevation view of the bar indicator.

Fig. 9 is a perspective view of a few of the piano key contacts underlying the F, F sharp and G keys.

Fig. 10 is an elevation view of an alternative form of electrical contact closure device operable by a natural note key such as the F key.

Fig. 11 is an elevation view of contact closure devices of the kind shown in Fig. 10 but cooperating with a black key such as the F sharp key.

Referring to Fig. 1, it is seen that the strip or sheet 20 is drawn from a roll 21 at the right and advanced over a curved guide or platen 22 toward the left, where a pair of pin wheels 23 engage marginal holes therein. All the sheet feeding and recording devices are supported on a base 24 and between side frames (not shown).

Between the side frames there is fastened a heavy curved support frame 25 upon which are mounted the recording devices and sheet tension rollers 26 and 27.

Turning to Fig. 2, it is noted that the strip 20 is prearranged with a complete set of printed staff lines 28, bar lines 29 and beat lines 30, the vertical lines being optional and omitted when changes in time are contemplated. Marginal perforations 31 are uniform in spacing and size with the exception of the elongated perforations 32 opposite the bar marker lines 29. These long perforations 32 are sensed by a bar indicator for giving both visual and audible indications of the time of passage of a bar of music as pointed out more fully hereinafter.

Fig. 3 shows sheet 20 having an extra layer of removable carbon material 33 or any other expedient known to leave a mark or impression when pressure is brought to bear in the form of a type shape.

Turning again to Fig. 1, record roll 21 is seen to be supported on a standard 36 fastened to the base. Sheet 20, before passing onto the platen, encounters the transverse tension roller 26 the ends of which are guided vertically in slots 37 formed in a pair of hangers 38. After passing the left end of platen 22, the sheet passes under the similar roller 27 suspended from hangers 39.

A motor M is connected by a belt 45 with a gear box 46 from which there projects a pinion 47 in mesh with an idler gear 48. Idler 48 meshes also with a pinion 49 fastened to the shaft 50 carrying the pin feed wheels 23. The whole pin wheel assembly is rotatably supported between a pair of bearing standards 51 fastened to the base.

Motor M is wired to the power source by wires 52 leading to a switch box 53 containing the main switch 54. It is contemplated that this box 53 will be placed on or near the piano to be near the composer, so that not only will he be able to reach switch 54 for initiation of the sheet feed but also operate buttons 55-59 to vary the tempo from presto, allegro, adagio and largo to lento. The buttons control various resistances as selective rheostats to change the motor speed and sheet movement as desired. Another reason why box 53 should be near the composer is because it contains the flashing light L for indicating the passage of bar marks 29 on the sheet past the initial print position.

From the foregoing it will be apparent that, after the motor M is started by switch 54 and regulated by a button 55-59, pin wheels 23 will be rotated counterclockwise and draw the sheet 20 from right to left under the printing devices 75 at a desired speed.

There is given an audible indication of the passage of each beat line 30 (Fig. 2) past the recording station. This is done by a cam 60 (Fig. 1) fastened to the shaft of a pin wheel 61 which is driven by the marginal perforations 31 of the note sheet 28. Wheel 61 is so proportioned that each revolution represents a sheet length of one beat. For different times, different size wheels 61 and different cam arrangements can be used to sound out the beats. In the path of cam 60 is the free end of a lever 63 pivoted at 64. The lever carries a weight which cooperates with a sounding box 65. As the sheet 28 is advanced, wheel 61 is rotated counterclockwise and cam 60 lifts lever 63 and drops it on the sounding box to indicate the beats of each measure.

The passage of each bar of note sheet area is indicated both visually and audibly as noted in Fig. 8. There it is seen that adjacent the recording start position is placed a sensing finger 66 which is electrically conductive and cooperating with a conductive part of platen 22. A compression spring presses the finger down on the sheet. The finger rests on the margin of the sheet 28 (Fig. 2) in the path of the inner portion of elongated openings 32 which, it will be remembered, are coincident with the bar markings 29. Therefore, upon the passage of each bar marking at the initial print position finger 66 projects through the note sheet and establishes electrical contact momentarily. A circuit is established including wire 67, battery 68, lamp L, bell 69, finger 66 and platen 22. As noted hereinbefore, the lamp L is seated in the control box 53 (Fig. 1) to be located within easy reach and within the range of vision of the composer. The sound indication given by the bell 69 is distinctive and readily differentiated from that given by the beat indicator box 65. When the composer is to start recording he will wait for the bar indication before striking the first note in order that the notes may be properly placed with relation to the bar and beat lines.

A set of note recorders is provided for each note position on the recording sheet and corresponding to each key of a piano. In Fig. 1 it is seen that eight note recorders are positioned along the top of the heavy frame 25 and along the path of the record sheet as the path is from right to left over the platen 22. There is such a set of recording devices for each note line 28 (Fig. 2), and each horizontal note space 18 provided for the complete range of piano key control as shown on the record sheet. Although only one set of recording devices is shown, it will be realized that the others are duplicates thereof and function the same as the manner about to be described.

The note recorders are all of the same construction and vary mainly in the shape of the type faces for recording the various note shapes representative of different times and of the sharp and flat notations. Since the note sheet is being advanced from right to left, the point at which the sheet 28 comes on to the platen 22 at the right is the initial recording position, and the recording devices vary in their note shapes from right to left according to the time interval through which the music passes and the sheet advances from right to left. Accordingly, the sharp and flat recorders SR and FR are placed at the extreme right and the note recording controls follow directly thereafter led by the $\frac{1}{8}$ note recorder $\frac{1}{8}R$. Continuing in a right to left order across the recording controls, it is seen that the $\frac{1}{8}$ note recorder $\frac{1}{8}R$ is next and then further

to the left is the $\frac{1}{4}$ note recorder $\frac{1}{4}R$ followed in succession by the $\frac{1}{2}$, $\frac{3}{4}$ and full note recorders $\frac{1}{2}R$, $\frac{3}{4}R$ and $1R$. Since all of these recorders are similar in construction with the exception of type face, it will be sufficient to describe one of them, for example, the centralized $\frac{1}{2}$ note recorder $\frac{1}{2}R$.

Each recorder includes a frame 70 secured to the curved top of the main cross frame 25. Each recorder frame is shaped with a shelf upon which is fastened an operating magnet 74 with which there cooperates an L-shaped armature lever 73 pivoted at 72 on the frame 70. A compression spring 75 presses between a shelf and the under side of the armature lever and tends to hold it elevated so that the lower end of its vertical portion is poised above the record sheet 28. The vertical portion of the armature lever 73 projects through an opening 76 in the frame 25, and the bottom end of the lever is formed with or carries a type face shaped with the well known $\frac{1}{2}$ note configuration. Frame 70 is formed with an upper hook-shaped projection 74 overlying the horizontal portion of armature lever 73 to act as a stop for it and to dampen vibration when it is released to the non-print position. It is apparent that, when magnet 74 is energized, lever 73 will be rocked in a counterclockwise direction and the lower end thereof will be pressed or struck against the sheet 28 supported by the platen 22.

The other note printers function in the same fashion as that described in connection with the $\frac{1}{2}$ note recorder $\frac{1}{2}R$, the only difference being in the note shapes produced thereby and the circuit connections for varying their time of selection either before or after the $\frac{1}{2}$ note recording, according to the length of time that the corresponding piano key is held down. As about to be described in connection with the timing mechanism, when the piano key is struck sharply or held down for a very short interval of time, the $\frac{1}{8}$ note recorder $\frac{1}{8}R$ becomes effective and for longer intervals of depression the other note recorders become progressively effective, only one of them being selected for any single note or single depression recording. The successive selection of a whole set of recorders is effected upon a depression of the piano key, but the actual selection of the particular one of the six note recorders is dependent upon the time of release of the same piano key. In other words, the magnet of any recorder is not energized immediately upon operation of a piano key but awaits the release of said key which determines the time interval and the proper note recording.

In order to effect time recording and note selection control, there is wired in series with each set of note recorders, and the contacts operated by the corresponding piano key, a timing commutator operated in synchronism with the advance of the record sheet. At the lower left corner of Fig. 1, it is seen that a pinion 80 extends from the gear box 46 which, it will be remembered, is part of the driving mechanism for advancing the record sheet. In mesh with this pinion 80 is a gear 81 fastened to a commutator drive shaft 82 extending across the machine and supported in side frame bearings. Pivotedly mounted on shaft 82 is a complete set of commutator contact arms 83, there being one for each note position and each set of recording devices. The hubs of arms 83 are recessed to receive magnetic clutches 84 and 85 which, when

energized, clamp the related arm to the shaft 82 to partake of its counterclockwise motion.

The ends of the commutator levers 83 cooperate with separate sets of separated contact plates H, $\frac{1}{16}N$, $\frac{1}{8}N$, $\frac{1}{4}N$, $\frac{1}{2}N$, $\frac{3}{4}N$ and 1N, relating to the home position and to the $\frac{1}{16}N$, $\frac{1}{8}N$, $\frac{1}{4}N$, $\frac{1}{2}N$, $\frac{3}{4}N$ and full note recorders, respectively. The plates are arranged in an arcuate formation on an insulation frame 87 secured to base 24. The sets of plates are insulated from each other and the plates of each set are further separated by insulation to be electrically distinctive. There are end stops confining the swing of the levers in both directions.

As a piano key is struck, the related lever 83 starts to swing counterclockwise and contact with the plates $\frac{1}{16}N$ to 1N successively in the order of relation to notes of successively longer time value. At the recording time, the lever is declutched, stopped and, as an aid to gravity, an associated restoration coil 89 is energized to attract the lever extension 90 and pull the lever down rapidly to the home position and ready to start up to record another note. All restoration coils 89 are supported on a standard 91 fastened to the top of base 24.

It is noted hereinbefore that each set of recording elements shown in Fig. 1 contain, in addition to the six note printers, two flat and sharp recorders FR and SR. This allocation of sharp and flat recorders does not apply to all sets of note recorders because it will be remembered that on the keyboard of a piano the black keys do not appear between all natural note white keys; for example, between the E and F keys (Fig. 5) there is no black key and, therefore, no call for the recording of E sharp or F flat. The absence of such sharp and flat recorders is shown diagrammatically in Fig. 4 by the blocks designated E1 and E2. There it is also noted that the sharp and flat recorders FR and SR related to the black key between the F and G keys are not both in alignment with the recording position of F. The sharp sign is in alignment with the space wherein F notes are recorded, but the flat sign is elevated one step to coincide with the G line, because it is in association with the G note recording that the flat type is to operate when the black key is operated between the F and G keys and pedals are operated to select flat recording in preference to sharp recording. The positions of several of the other sharp and flat recorders are shown in proper alignment at the right of Fig. 4 and the omissions of the unnecessary recorders are also noted by the absence of signs and presence of cross hatching within the blocks between the various recorders.

At the top of Fig. 1 there are shown three views of two adjacent piano keys, the F key and the F sharp key FS. Although the showing of these keys is spread out, it will be understood that they are to remain in the positions they ordinarily occupy in the regular piano keyboard. It is also well to note that these key and key contact showings are merely diagrammatic and representative of a full set of keys and key contacts cooperating with all of the keys of the full piano keyboard. In general, the contact associated with the key F at the left are related to circuits brought into operation when the natural note key is operated alone. The contacts and circuits associated with the key of the middle showing are related to circuits brought into operation by actuation of black keys, such as the F sharp key FS, in selecting the same circuits selected when the F key is

operated alone. In other words, each black key has pairs of sets of circuits associated therewith for calling into operation the recording of either the adjacent natural note keys according to pre-selection of sharp or flat operation. In the illustration, it is assumed that selection for sharp recording is made and, therefore, when the black key FS is operated the circuits for recording F notes are called into play in preference to the recording of G notes when a flat selection is made.

The key showing at the upper right hand corner of Fig. 1 relates to a pair of circuits operated directly by the F sharp key FS for selecting recording of either a sharp mark in association with an F note or a flat mark in association with a G note.

Considering first the ordinary recording of natural notes by the operation of white keys alone, for example, upon the depression of the F key and its subsequent release, a number of circuits are established for starting the commutator, stopping the commutator, effecting recording and effecting restoration of the commutator. The contact devices are mounted in a U-shaped insulation frame 95 which has embedded therein a series of upper and lower contact plates 96 and 97, there being a pair of such plates for each natural note key. Also mounted within said frame 95 is a pair of swinging contact blades Fⁿ and F^{n'} fastened to shoulders at the upper and lower part of the left end of the frame. The right ends of said blades Fⁿ are free and resting upon the upper and lower surfaces of the natural note key F. Immediately upon depression of the key F, a circuit is established for clutching the related commutator contact arm 83, said circuit including wire 100, battery 101, wire 102, clutch coil 85, the opposite clutch coil 84, wire 103, contact blade F^{n'} and contact plate 97. By means of this circuit the commutator contact arm is connected to shaft 82 and starts swinging counterclockwise to pass over the different note selecting plates $\frac{1}{16}N$, $\frac{1}{8}N$, etc. As long as the key is held depressed, the circuit described is the only one effective and remains effective until the time that the key is released, which is an indication of the length of time that the note was held and then other circuits are called into effect to cause recording and restoration.

The recording circuit is established at the time the key is released and at the instant that the lower contact remains made and when the upper contact is established. The recording control circuit includes wire 105, battery 106, wire 107, commutator contact arm 83, and then to any one of the several note selecting plates, for example the $\frac{1}{2}$ note contact plate $\frac{1}{2}N$, wire 108, magnet 74, wires 109, 110, 111 and 112 to contact plate 96 and then through upper blade Fⁿ connecting wire 113, lower blade F^{n'}, plate 97, and back to wire 105. The circuit path through commutator lever 83 is possible because the lever is insulated with respect to the other electrical circuits associated therewith, for example, the clutch coils 84 and 85. The recording circuit is of a momentary duration but sufficient to cause energization of magnet 74 to attract recording lever 73 and force it down on the record sheet 20 to place the impression of a $\frac{1}{2}$ note in the F position between staff lines.

At the instant that the recording operation is effected, it is desired to cause speedy restoration of the commutator arm, so that should a second F note follow rapidly upon the heels of

the one recorded, the devices will be able to take up the timing of the new note and record the proper value. In order to facilitate restoration of the commutator arms, there is an attractive restoration magnet 89 associated with each arm and a circuit is established thereto upon the release of the associated key. The circuit includes the upper contact blade Fn, contact plate 96, wire 115, magnet 89, wire 116, battery 117, wire 118, back to the blade Fn.

The foregoing circuits relate to recording of natural notes directly through natural note keys. However, there are times when a black key is operated and a recording must be made of an adjacent natural note without the accompanying operation of the natural note key. For example, when the F sharp key is operated, it is not only effective to record a sharp mark alone, but the accompanying F note must be recorded along therewith. Although the showing in Fig. 1 relates to selection of recording an F note under control of the key FS, it will be realized that a similar set of circuit connections are established to the adjacent G key contacts for selection of G note recording when a selection is made to effect flat recording in preference to sharp recording. However, the circuits about to be dealt with are concerned with selecting F note recording under control of the F sharp key FS, assuming that selection has been made for sharp recording in preference to flat recording. The two contact blades Fs and Fs' cooperating with the sharp key Fs are formed with extending portions shown better in Fig. 9, where it is seen that they extend from underneath the F natural key over toward the right in the path of the upper and lower surfaces of the F sharp key Fs. Although only the bottom layer of contact blades is shown in Fig. 9, it is easy to imagine the other set of similar contact blades overlying the piano keys which are located between the two sets of contacts. For purposes of easy assembly, the U-shaped insulation contact holder 95 may be made in two or more parts assembled in recesses formed in the piano keyboard frame.

Turning now to the first circuit selected by the depression of the F sharp key Fs (Fig. 1), it is noted that the contact blade Fs' is depressed against a separate contact plate 97s to which there is attached a wire 120 leading to the wire 100 already described as forming part of the ordinary natural note start circuit. The circuit continues through battery 101, armature clutch coils 84 and 85, wire 103, wire 121, contacts closed by a sharp selecting plate 2S and wire 122, back to the blade Fs'. Therefore, the natural note control commutator is started from the sharp key as well as from the natural note key.

Recording under control of the sharp key is effected in the same manner as it was under control of the natural note key, the only difference being that the two contact blades Fs and Fs' are operated by the black key and natural note recording is made selectable through the manipulative sharp and flat selectors. The circuit for recording is made at the time the sharp key is released and, at the instant that the upper and lower blades are both effective in connection with the stationary contact plates, the lower blade Fs' contacts plate 97s, to which is attached wire 123 leading to the sharp selection contacts closed by plate 3S, and from there a wire 125 is connected to the wire 105 already mentioned. The recording circuit continues through battery 106, wire 107, commutator arm 83, a commutator plate

such as $\frac{1}{2}N$, wire 108, magnet 14, wires 109, 110 111, 126 to the upper contact plate 96s, blade Fs and wire 127 connecting the upper and lower movable blades.

5 It will be understood that in order to avoid back circuits a number of circuit directing rectifiers or other switching devices may be provided between the different circuits selected for natural, sharp or flat note recording.

10 Another circuit selected by operation of the sharp key FS is that for effecting restoration of the commutator devices. This circuit includes the upper contact blade Fs, the stationary plate 96s, wire 130, wire 115, magnet 89, wire 116, 15 battery 117, wire 118, wire 131, the sharp selection contacts closed by plate 4S, and wire 132 back to the blade Fs.

The sharp key FS has another function and that is to select immediate recording of either a sharp or flat notation to be placed on the record sheet immediately upon the operation of a black key.

20 The sharp or flat mark so placed travels toward the left on the record sheet 20 and appears under the various related note recording positions in synchronism with the passage of time of the commutator selector. In other words, although the flat or sharp notation is made at the right of the recorded devices, it is advanced proportionately toward the proper note printer

25 30 which is to be selected as time advances. Therefore, the recording of a note of the proper time value will be recorded in association with the sharp or flat mark as it appears under the recording station. Returning to consideration of 35 the circuit connections for effecting the recording of a sharp or flat note (in the present instance a sharp notation to be associated with the F note), it is seen in Fig. 9 that the centralized contact blade FS_k is directly under the black key.

40 Returning to Fig. 1 and the key view at the upper right corner, it is noted that under blade FS_k is provided a stationary contact plate 97s' is so located in insulation frame 95 that its left end is directly under the rounded portion of the

45 contact blade. The proportions are such that upon depression of the sharp key contact is established and immediately broken, because further movement of the blade FS_k in a downward direction causes the rounded portion to move

50 toward the left away from the contact plate 97s'. The sharp notation selecting circuit includes a wire 134, battery 135, magnet 136 in the sharp recording unit SR, wire 137, the sharp selecting contacts closed by the sharp selecting plate 1S, wire 138, contact plate 97s' and blade FS_k.

55 As an alternative to the selection of the sharp notation, selection of the flat notation by the same key FS is produced by closure of plate 1F upon its contacts in preference to closure of plate 1S upon its contacts. The resulting flat notation circuit is the same as that described, the only difference being its direction through the magnet of the flat recorder FR and the selection plate 1F and the connecting wiring 140 and 141.

60 Regarding the flat and sharp recording circuits shown in Fig. 1, it is noted that they are independent of the commutator. However, if desired, the sharp and flat recording circuits can be directed through the commutator arm 83 and the home position contact plate H of the related note to insure that the notation is recorded early in the cycle to cooperate with the related natural note recording or not at all.

The view shown in Fig. 5 is mainly a repetition of the controls shown in Fig. 1 with the exception of disclosure of the sharp and flat selection controls and the alternative mode of printing by photography instead of impact hammers. Most of the control circuits of Fig. 1 are repeated in Fig. 5 with the exception of the commutator arm restoring circuit. Fig. 5 also differs in that a few representative piano keys are shown in a plan view rather than a side elevation.

Although in Fig. 5 the sharp and flat recording circuits are shown singly and separately associated with the E flat and F sharp keys, it will be understood that circuits of this kind are duplicated for each of the flat keys and related circuits are also duplicated for each of the adjacent natural note keys. For example, the G key will have associated therewith not only its separate natural note circuits but also both of the G flat and G sharp recording controls associated with both adjacent black keys.

It is pointed out hereinbefore with reference to Fig. 1 that a number of selection plates 1S to 4S and 1F to 4F are associated with those circuits selective of either sharp or flat printing notation. In Fig. 5 it is seen that these sets of four plates are separately mounted and controlled by foot pedals 150 and 151 which operate to lift them selectively into register with associated contacts. The sharp control pedal 151 carries a large oblong block of insulation represented diagrammatically at 153 for holding the sets of sharp plates for all the black keys. In a similar way the flat selection control pedal 150 carries a block 152 for swinging all the sets of flat circuit controlling plates into contact with the related selection contacts of all black keys.

The pedal selection control described is an optional one in that it provides for complete flat or sharp control across the entire keyboard. In other words, the selection is flexible only to the degree of choosing one or the other of the flat or sharp notations. As an alternative to this, the pedals 150 and 151 may represent separate finger pieces or keys, each of which is controlling for only those four plates related to one black key, with the provision of a complete series of such hand operated pairs of flat and sharp controls preferably located near the keyboard. In other words, the recording of each black key representation could be selective or eliminated entirely at the will of the operator. Across any of the pairs of contacts opposite plates, such as 1F and 1S, there may be placed a switch to cause fixed control, or such a switch in series could effect control elimination regardless of the pedal positions.

Before tracing the recording control circuits shown in Fig. 5, it is believed best to explain the alternative method of recording by photography represented at the left side of Fig. 5 and in the adjacent Figs. 6 and 7. Taking, for example, the $\frac{1}{4}$ note recorder $\frac{1}{4}P$ at the left side of Fig. 5, it is seen that the note recorder is located in a light-proof box NP which is fixed over an opening 160 which is either shaped to represent the note to be recorded as shown in Fig. 7 or is shaped square to be receptive at any plane along its length to a mask 161 in which an opaque material has a transparent shape representative of the $\frac{1}{4}$ note. Within the recording box is a light bulb 163 which is switched on automatically simultaneous with the actuation of magnets 164 for opening a pair of shutters 165 pivoted at 166 on the sides of the box. In the plan view (Fig.

6), it is seen that the shutters are mounted in cooperating pairs and drawn together by pairs of springs 167 attached to opposite shutters at their ends so as to normally hold them closed in upper position. When the cooperating pair of magnets 164 is energized, the two shutters are swung downwardly to form a centralized opening coincident with the mask opening 160 in the main frame 25F. Therefore, the light from bulb 163 is permitted to pass through the photographic recorder in the desired shape and be cast on the recording film 20F. The circuits for causing such photographic exposure are arranged to be momentary in time and therefore a sharp 15 image is recorded on the film.

It is understood that there is a complete set of note recorders extending across the printing frame for the photographic recording control just as there is in the pressure printing control modification shown in connection with Fig. 1. The sharp and flat photographic recorders SP and FP are placed with relation to the associated natural note lines and spaces as shown in Fig. 4.

Returning now to consideration of the circuits 25 for effecting recording through the sharp and flat selectors, it is noted that upon depression of the F sharp key FS a circuit is established for sharp recording including wire 138, contact plate 1S, wire 137, the sharp recorder SP, for energizing the enclosed bulb and the associated magnet 136P. These two photographic controls may be wired in series or in parallel to be active at the same time and the related shutter is of a single form rather than dual as in connection with 30 the natural note recorders. The circuit continues through wire 133, battery 135, wire 134 and contact FS_k, said contact being effective in connection with a plate such as plate 97's' (Fig. 1).

As an alternative to the selection of a sharp 40 notation control, a second circuit may be traced assuming that there is flat selection. This circuit is shown in association with the E flat key EF for purposes of illustration spacing. However, it will be understood that the F sharp key FS 45 has a similar set of controls which are not illustrated therewith because of the confusion of lines that would result from such a dual showing. The flat notation control circuit extends from under the E flat key EF, through wire 140, contact plate 1F, wire 141, the flat recorder FP, wire 133e, battery 135e, wire 134e, key contact EF_k, and the underlying contact plate connected to wire 140.

Along with the recording of the selected sharp 50 and flat notations there is a selected recorder 55 for the natural note which is also determined by selection plates 2S or 2F. These plates control the clutching of the commutator to start the timing devices for choosing the note of the proper 60 time value. Assuming that the sharp notation control has been selected, then the commutator arm relating to the F note recorder is started 65 swinging by the following circuit. Associated with the underlying F sharp contacts FS is the wire 121 extending to contacts cooperating with plate 2S. From there the circuit continues 70 through wire 122, battery 101, wire 102, and through the clutch coils of magnets in related arm 83 and back through wire 103 to the contact plate opposite the movable blade F's. This circuit remains established to continue the swing 75 of the commutator arm as long as the related piano key is held depressed. A similar circuit is closed through the flat recording control as illustrated in connection with the E key. There the

circuit includes wire 124e, contact plate 2F, wire 122e, battery 104e, wire 102e, the clutch coil in the commutator arm 83 relating to the E note recorder and back to the key contacts through wire 103e to the movable blades Ef underlying the E and E flat keys.

When the key is lifted, the recording circuit is established through the commutator along the following path. Assuming that the sharp notation has been selected, then the circuit passes through wire 124, plate 3S, wire 125, wire 105, battery 106, wire 107, arm 83, commutator plate 1Nf, wire 108 to the $\frac{1}{16}$ note recorder $\frac{1}{16}$ P, wire 109, wire 112, and over to the sharp selection blade Fs, and then through the underlying contact plate and over to the wire 124 to complete the circuit.

Should the flat notation be selected in preference to the sharp notation, then the natural note recording under control of the adjacent black key EF is selected by a circuit as follows: wire 124e, plate 3F, wire 125e, battery 106e, wire 107e, arm 83, commutator plate 1Ne, wire 108e, the $\frac{1}{16}$ note recorder $\frac{1}{16}$ P, wire 109e, wire 112e, and contact blade Ef cooperating with contact plate connected to wire 124e.

The commutator restoring circuits associated with selection plates 4S and 4F are not shown, since they merely act to pull down the commutator arms. In tracing the recorder control circuits to the photographic units at the left in Fig. 5, it is realized that certain of the units relate to the E key while others relate to the F key and, therefore, they will be in two separate lines of recorders. In order to coincide with the sample circuits traced, the $\frac{1}{8}$ note recorder $\frac{1}{8}$ P and the flat notation recorder FP are one step nearer the observer of Fig. 5 than the other three photographic recorders shown.

As an alternative to the contact blades shown in cooperation with the piano keys of Figs. 1 and 5, there are provided the contact closing devices shown in Figs. 10 and 11, the first mentioned figure showing contacts associated with a natural note key, such as F, and the other view showing the contacts associated with a black key such as F sharp key FS. In Fig. 10 it is shown that underlying the F key is a standard 170 upon which is pivoted at 171 a lever 172, the upper end of which is in contact with the lower portion of the piano key. Cooperating with the top edge of lever 172 is the lower blade of a pair of contacts Fna which are closed immediately upon depression of the key and remain closed as long as the key is operated.

Pivoted at 173 on lever 172 is a flipper 174 with an offset projection 175 cooperating with two upper blades of pairs of contacts Fnc and Fnb which are not operated on the down stroke of the piano key. The reason they are not operated is apparent from the construction of flipper 174 which is held in position by spring 176 connected to a stop lug 177 on the flipper which is so located that upon clockwise movement of lever 172 the flipper is permitted to turn in a counter-clockwise direction and escape past the ends of the contact blades. However, when the piano key is released a spring 178 attached to the lever pulls down the flipper and then said flipper is pressed through the extension 177 and acts in a positive manner to depress the upper blades and close the pairs of contacts Fnd and Fnc momentarily to cause printing and restoration of the commutator devices. It is evident that contacts Fna can be connected in the circuit between wires 100

and 103 (Fig. 1) to take the place of contact Fn' and plate 97. Contacts Fnb and Fnc can be substituted for the other controls of the natural note circuits.

In Fig. 11 it is seen that associated with a black key FS is a lever 172' operating in the same fashion as the lever 172 described with reference to Fig. 10. This lever 172' also carries a flipper 174' which is similar in construction and operation to the flipper 174 (Fig. 10) already mentioned. It cooperates with the upper blades of pairs of contacts Fsb and Fsc which leads to sharp or flat controls before being connected to the circuits for the natural note recording and restoring mechanisms. Resting on the upper part of lever 172' is the lower blade of a pair of contacts Fsa for energizing the commutator in a fashion somewhat similar to that exercised by the contacts Fna of Fig. 10 and F's of Fig. 1.

The other difference shown between controls of Fig. 11 over those in Fig. 10 is that residing in the provision of the extra flipper 180 pivoted at 181 near the top of lever 172'. This flipper is provided for the purpose of making an early and instantaneous closure of a circuit to the flat or sharp recorder. In the present instance the cooperating contact is identified as contact FSka, the lower blade of which is raised immediately upon the clockwise rotation of lever 172' by a depression of the F sharp key FS. The closure is momentary before the escape of the flipper past the lower blade, and upon the return stroke of lever 172', and there is no further action because the extension on the flipper then moves away from the supporting lever and is snapped back into the normal position by a spring 182 drawn between the two flippers. Contact FSka may be substituted for the contact FSk of Fig. 1.

If the construction is independent of sharp and flat selection control, then the lever 172 shown in Fig. 10 may be used in cooperation with the black key shown in Fig. 11 by merely placing an offset extension thereon to underlie the related sharp or flat key. However, in the construction shown it is possible that the black key may be representative of either adjacent natural note key. Therefore, in Fig. 11 in addition to the lever 172', which is representative of F sharp recording, there is also present a similar lever GF which is representative and controlling over contacts leading to circuits for effecting a G note recording along with a G flat notation. When the black key is independent of selective sharp or flat control levers, such as 172' and GF, there is still need of a lever for carrying a flipper such as flipper 180 to control the effecting of sharp or flat notation along with the depression of the black key.

While there have been shown and described and pointed out the fundamental novel features of the invention as applied to a modification, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In a music recorder, a series of photographic music note recording elements, a manipulative part of an instrument, means under control of said part for selecting one of said elements according to the time interval between operation and release of said part, and means for record-

ing a note shape on a film under control of the selected element.

2. In a music recorder, a plurality of sets of photographic music note recording elements, a timer for each set of said recording elements, a manipulative control for each of said timers, said control being vibrated in connection with operation of a musical instrument, and means cooperating with said control and affected by said vibrations to cause said timer to select one of a series of said recording elements, and means cooperating with said recording element for recording a note shape on a film.

3. In a music recording device, a set of keys, photographic recording instrumentalities including a plurality of note recording members with electrical connections to each of said keys, means under control of said keys for selecting one of said recording members for each operated key according to the time interval of operation, and means for effecting photographic music note recording under control of the selected members.

4. In a device for recording music on a sheet with a full staff area for recording notes, sets of photographic devices, one set for each note position, each set comprising masks for a series of note shapes, a plurality of manipulative operating controls for a musical instrument, and means under control of selected ones of said operating controls for directing light through selected masks of said devices.

5. In a music recording device, a set of operating keys, recording instrumentalities with a plurality of lightproof boxes containing note shaped masks for each key, light flashing means for said boxes, means under control of each key as determined by the duration of operation thereof for selecting one of each plurality of boxes and flashing said light means therein, and means for continuously advancing a recording film under the masks of said boxes to receive photographic impressions of music note shapes directed thereon.

6. The combination set forth in claim 5, wherein said lightproof boxes each contain shutter devices which are electrically controlled to be opened simultaneously with the operation of the light flashing means.

7. In a device for recording musical notation on a note strip under control of a musical instrument with operating instrumentalities, a series of photographic recording means located in alignment in juxtaposition with the sensitized surface of said note strip, and means under control of said operating instrumentalities for operating one or more of said photographic means to record on said strip actual note shapes displaced on the strip according to the tone values of the operated instrumentalities.

8. The invention according to claim 7 characterized by the provision of a plurality of sets of photographic means, each set relating to a particular tone value and various photographic means of a set relating to the different time values of the particular tone, and means associated with each operating instrumentality for timing the operating interval thereof and thereby selecting the sets and particular photographic means of the set to record actual note shapes of a tone and time value in the proper staff positions on the note strip.

9. The invention according to claim 7 characterized by the provision of sharp and flat photographic recording means, and means under con-

trol of the operating instrumentalities for selecting operation of said sharp and flat photographic recording means along with the recording of related natural note photographic recording means.

5 10. In a music recording device operated by an instrument with operating instrumentalities, a plurality of sets of photographic recording means each comprising a light source, a shutter and a mask shaped with one of a plurality of music note shapes, and means under control of said operating instrumentalities for operating the lights and shutters of selected photographic recording means.

15 11. The invention set forth in claim 10, further characterized by the provision of pairs of lights and shutters and sharp and flat masks related to sets of natural note photographic recording means, and means for selectively operating either of said sharp or flat, lights and shutters in cooperation with the operation of the natural note photographic recording means.

20 12. The combination set forth in claim 10 wherein the light source is common to all recording means and independent of said operating instrumentalities.

25 13. In a music recording device for recording on a note strip under control of the operating instrumentalities of a musical instrument, a pair of electrical contacts arranged under and another pair of contacts arranged over said operating instrumentalities, recording devices, means under control of said pair of contacts under said instrumentalities for initiating operation of said recording devices, and means under control of said another pair of overlying contacts operated by said instrumentalities for terminating operation of said recording devices.

30 14. The invention set forth in claim 13, further characterized by the provision of sharp and flat controls with overlapping contact devices common to said sharp and flat controls and natural note instrumentalities, and means under control of the sharp and flat controls for operating the electrical control means of adjacent natural note instrumentalities.

35 15. Musical composition writing apparatus, including means for selectively propelling a band of music score paper at any one of several predetermined speeds, whose ratio to each other is more or less approximately the metronomic ratio between the several metronomic tempos, a series of sets of electromagnetic natural note markers and intermediate note markers in operative juxtaposition to said band and extending across the band in operative alignment to the corresponding natural staff positions, and arranged to make an impression on the paper, a piano keyboard with natural and intermediate (sharp or flat) 40 keys, electric circuit contacts disposed above and beneath each natural key of the piano keyboard, and adapted to be operated thereby, other electric circuit contacts corresponding to each intermediate key which is also effective to operate the first mentioned contacts beneath and above the natural key immediately adjacent to it, a timing 45 commutator selector arm for each set of markers, electric circuits to magnetic clutch means between said propelling means and each selector 50 arm, with each arm started in operation by closure of related natural and intermediate contacts, other electric circuits connected to each of said electrical circuit contacts of the natural 55 keys and through a related selector arm to the 60 first mentioned contacts beneath and above the natural key immediately adjacent to it, a timing 65 commutator selector arm for each set of markers, electric circuits to magnetic clutch means between said propelling means and each selector arm, with each arm started in operation by closure of related natural and intermediate contacts, other electric circuits connected to each of said electrical circuit contacts of the natural 70 keys and through a related selector arm to the 75 electromagnetic markers corresponding to the

natural notes for moving one of said markers into contact with the paper, and other electric circuits connected to each of said other contacts beneath and above each of the intermediate (sharp or flat) keys and each of said intermediate note electromagnetic markers, for moving said markers into marking position for each movement of a related intermediate key, and for thereafter releasing the marker from the marking position, and still other electric circuits for each of said electric circuit contacts beneath and above each key including electromagnetic restoring means for the operated arms.

16. The method of recording musical notation directly from a played instrument, comprising the steps of feeding a photographic film at a selected rate, operating a contactor at the same rate, manipulatively starting and stopping said contactor, selecting a note shape by virtue of the elapsed timing of said contactor, and opening and closing photographic shutter devices to flash images of selected music note shapes on said film.

17. In a music recording device for recording on a coated paper strip, actual note shapes of whole, half, three-quarter, etc., notes of the entire range, and sharp and flat marks associated therewith under control of the keys of a piano, said strip being ruled with a complete set of staff lines extending lengthwise of the strip, and measure lines across the strip with intermediate beat lines, said strip having marginal feed perforations with spaced special perforations coinciding with the measure length, pairs of contacts under and over each white natural note key, other pairs of sharp and flat control contacts for each natural note white key cooperating with adjacent black keys and operated thereby, pairs of contacts for each black key, pedal operated selecting means for making effective either the sharp or flat contacts operated by the black keys, a motor, a switch therefor, a series of speed changing tempo devices cooperating with said motor, manipulative tempo controls for said speed changing devices, toothed feeding means cooperating with the paper strip, a train of gearing between said motor and said feeding means, a toothed timing means operated by said marginal perforations, cam means on said timing means, sounding devices operated by said cam means to sound beat intervals, a sensing means resting on said strip in alignment with said margin perforations to detect the special measure length perforations, light flashing means and sounding means under control of said sensing means for indicating the appearance of a measure line at the recording position and the passage of a measure length on the strip, a common panel containing said switch, said tempo controls and said measure indicating means for placement near the piano, a plurality of sets of recording devices, one set for each natural note key on the piano and comprising sharp, flat, $\frac{1}{8}$ note, $\frac{1}{8}$ note, $\frac{1}{4}$ note, $\frac{1}{2}$ note, $\frac{3}{4}$ note, and whole note recording devices, said recording devices being arranged in the order mentioned in the direction of feed of the strip, magnets for operating the recording devices, dual circuit connections between said black key contacts, the pedal operated selecting means and the sharp and flat recording devices whereby either device is operated momentarily by a key depression, electrical contact sectors, one for each white key, said sectors having individual contact segments connected to the magnets for the $\frac{1}{8}$ note, $\frac{1}{8}$ note, etc., recording de-

vices in the order mentioned, contact arms for said sectors, one arm normally alongside each segment for the $\frac{1}{8}$ note and provided to contact with the segments successively in synchronism with the passage of the record receiving point on the strip under the related recording devices, a magnetic clutch for connecting each arm to the drive gearing, a magnetic restoring means for each arm, triple starting circuit connections from the three pairs of contacts under a white key for operating the related clutch to start the arm swinging when a related key is depressed, one of the triple connections being operable directly by the contacts of the white key and the other two connections being operable by the contacts of one or the other of the adjacent black keys and selected by the pedal operated selecting means through which said two connections pass, triple recording circuit connections from the pairs of contacts over and under a white key and operated by the release thereof for energizing a selected one of the recording magnets according to the duration of key depression, one of said triple recording connections being operable directly by the contacts of the white key and the other two connections being operable by the contacts of one or the other of the adjacent black keys and selected by the pedal operated selecting means through which said two connections pass, triple restoring circuit connections from the three pairs of contacts over a white key for operating the related restoring means to restore said arm when the key is released, one of said triple restoring connections being operable directly by the contacts of the white key and the other two connections being operable by the contacts of one or the other of the adjacent black keys and selected by the pedal operated selecting means through which said two connections pass, whereby sharp, flat and natural note shapes of different time values can be recorded in the proper positions on said staff lined strip as the corresponding music is played.

18. In a music recording device for recording on a paper strip actual note shapes of whole, half, three-quarter, etc., notes of the entire range and sharp and flat marks associated therewith under control of the keys of a piano, said strip being ruled with a complete set of staff lines extending lengthwise of the strip, and measure lines across the strip with intermediate beat lines, said strip having marginal feed perforations, pairs of contacts under and over each white natural note key, other pairs of sharps and flat control contacts for each natural note white key cooperating with adjacent black keys and operated thereby, pairs of contacts for each black key, pedal operated selecting means for making effective either the sharp or flat contacts operated by the black keys, a motor, toothed feeding means cooperating with the paper strip, a train of gearing between said motor and said feeding means, a plurality of sets of recording devices, one set for each natural note key on the piano and comprising sharp, flat, $\frac{1}{8}$ note, $\frac{1}{8}$ note, $\frac{1}{4}$ note, $\frac{1}{2}$ note, $\frac{3}{4}$ note, and whole note recording devices, said recording devices being arranged in the order mentioned in the direction of feed of the strip, magnets for operating the recording devices, dual circuit connections between said black key contacts, the pedal operated selecting means and the sharp and flat recording devices whereby either device is operated momentarily by a key depression, electrical contact sectors, one for each

white key, said sectors having individual contact segments connected to the magnets for the $\frac{1}{16}$ note, $\frac{1}{8}$ note, etc., recording devices in the order mentioned, contact arms for said sectors, one arm normally alongside each segment for the $\frac{1}{16}$ note and provided to contact with the segments successively in synchronism with the passage of the record receiving point on the strip under the related recording devices, a magnetic clutch for connecting each arm to the drive gearing, a magnetic restoring means for each arm, dual starting circuit connections from said pairs of contacts under a white key for operating the related clutch to start the arm swinging when a related key is depressed, one of the dual connections being operable directly by the contacts of the white key and the other connection being operable by the contacts of the adjacent black key and selected by the pedal operated selecting means through which said other connection passes, dual recording circuit connections from the pairs of contacts over and under a white key and operated by the release thereof for energizing a selected one of the recording magnets according to the duration of key depression, one of said dual recording connections being operable directly by the contacts of the white key and the other connection being operable by the contacts of the adjacent black key and selected by the pedal operated selecting means through which said connection passes, dual restoring circuit connections from the said pairs of contacts over a white key for operating the related restoring means to restore said arm when the key is released, one of said dual restoring connections being operable directly by the contacts of the white key and the other connection being operable by the contacts of the adjacent black key and selected by the pedal operated selecting means through which said connection passes, whereby sharp, flat and natural note shapes of different time values can be recorded in the proper positions on said staff lined strip as the corresponding music is played.

19. In a music recording device for recording on a paper strip actual note shapes of whole, half, three-quarter, etc. notes of the entire range and sharp and flat marks associated therewith under control of the manipulative controls of a musical instrument, said strip being ruled with a complete set of staff lines extending lengthwise of the strip, and measure lines across the strip with intermediate beat lines, said strip having marginal feed perforations, pairs of contacts under and over each of said controls, other pairs of sharp and flat control contacts for each of said controls, toothed feeding means cooperating with the paper strip, a train of gearing between said motor and said feeding means, a sensing means resting on said strip in alignment with said margin perforations to detect the special measure length perforations, means under control of said sensing means for indicating the appearance of a measure line at the recording position and the passage of a measure length on the strip, a plurality of sets of recording devices, one set for each natural note and comprising sharp, flat, $\frac{1}{16}$ note, $\frac{1}{8}$ note, $\frac{1}{4}$ note, $\frac{1}{2}$ note, $\frac{3}{4}$ note, and whole note recording devices, said recording devices being arranged in the order mentioned in the direction of feed of the strip, magnets for operating the recording devices, electrical contact sectors, one for each of said controls, said sectors having individual contact segments connected to the magnets for the $\frac{1}{16}$ note, $\frac{1}{8}$ note, etc., recording devices in the order mentioned, contact arms

for said sectors, one arm normally alongside each segment for the $\frac{1}{16}$ note and provided to contact with the segments successively in synchronism with the passage of the record receiving point on the strip under the related recording devices, a magnetic clutch for connecting each arm to the drive gearing, a magnetic restoring means for each arm, starting circuit connections from the contacts under a control for operating the related clutch to start the arm swinging when a related control is operated, recording circuit connections from the pairs of contacts over and under a control and operated by the release thereof for energizing a selected one of the recording magnets according to the duration of control operation, restoring circuit connections from the pairs of contacts over a control for operating the related restoring means to restore said arm when the control is released, whereby sharp, flat and natural note shapes of different time values can be recorded in the proper positions on said staff lined strip as the corresponding music is played.

20. In a music recording device for recording on a paper strip actual note shapes of whole, half, three-quarter, etc. notes of the entire range and sharp and flat marks associated therewith under control of the keys of a piano, said strip being ruled with a complete set of staff lines extending lengthwise of the strip, and measure lines across the strip with intermediate beat lines, said strip having marginal feed perforations, pairs of operating instrumentalities under and over each white natural note key, other pairs of sharp and flat control instrumentalities for each natural note key cooperating with adjacent black keys and operated thereby, pairs of operating instrumentalities for each black key, pedal operated selecting means for making effective either the sharp or flat instrumentalities operated by the black keys, a motor, toothed feeding means cooperating with the paper strip, a train of gearing between said motor and said feeding means, a plurality of sets of recording devices, one set for each natural note key on the piano and comprising sharp, flat, $\frac{1}{16}$ note, $\frac{1}{8}$ note, $\frac{1}{4}$ note, $\frac{1}{2}$ note, $\frac{3}{4}$ note, and whole note recording devices, said recording devices being arranged in the order mentioned in the direction of feed of the strip, means for operating the recording devices, dual connections between said black key contacts, the pedal operated selecting means and the sharp and flat recording devices whereby either device is operated momentarily by a key depression, note selectors, one for each white key, said selectors having individual selecting means for the $\frac{1}{16}$ note, $\frac{1}{8}$ note, etc., recording devices in the order mentioned, a selector arm normally near the selecting means for the $\frac{1}{16}$ note and provided to operate with the selecting means successively in synchronism with the passage of the record receiving point on the strip under the related recording devices, a clutch for connecting each arm to the drive gearing, a restoring means for each arm, triple starting connections from the three pairs of operating instrumentalities under a white key for operating the related clutch to start the arm swinging when a related key is depressed, one of the triple connections being operable directly by the white key and the other two connections being operable by one or the other of the adjacent black keys and selected by the pedal operated selecting means through which said two connections pass, triple recording connections from the pairs of operating instrumen-

talities over and under a white key and operated by the release thereof for controlling a selected one of the recording means according to the duration of key depression, one of said triple recording connections being operable directly by the white key and the other two connections being operable by one or the other of the adjacent black keys and selected by the pedal operated selecting means through which said two connections pass, triple restoring connections from the three pairs of operating instrumentalities over a white key for operating the related restoring means to restore said arm when the key is released, one of said triple restoring connections being operable directly by the white key and the other two connections being operable by one or the other of the adjacent black keys and selected by the pedal operated selecting means through which said two connections pass, whereby sharp, flat and natural note shapes of different time values can be recorded in the proper positions on said staff lined strip as the corresponding music is played.

21. In a music recording device for recording on a strip actual note shapes of whole, half, three-quarter, etc. notes of the entire range and sharp and flat marks associated therewith under control of the keys of a piano, said strip being ruled with a complete set of staff lines extending lengthwise of the strip, pairs of contacts under and over each white natural note key, other pairs of sharp and flat control contacts for each natural note key cooperating with adjacent black keys and operated thereby, pairs of contacts for each black key, pedal operated selecting means for making effective either the sharp or flat contacts operated by the black keys, a motor, feeding means cooperating with the strip, a train of gearing between said motor and said feeding means, a plurality of sets of recording devices, one set for each natural note key on the piano and comprising sharp, flat, $\frac{1}{16}$ note, $\frac{1}{8}$ note, $\frac{1}{4}$ note, $\frac{1}{2}$ note, $\frac{3}{4}$ note and whole note recording devices, said recording devices being arranged in the order mentioned in the direction of feed of the strip, magnets for operating the recording devices, dual circuit connections between said black key contacts, the pedal operated selecting means and the sharp and flat recording devices whereby either device is operated momentarily by a key depression, electrical contact sectors, one for each white key, said sectors having individual contact segments connected to the magnets for the $\frac{1}{16}$ note, $\frac{1}{8}$ note, etc., recording devices in the order mentioned, contact arms for said sectors, one arm normally alongside each segment for the $\frac{1}{16}$ note and provided to contact with the segments successively in synchronism with the passage of the record receiving point on the strip under the related recording devices, a magnetic clutch for connecting each arm to the drive gearing, a magnetic restoring means for each arm, triple starting circuit connections from the three pairs of contacts under a white key for operating the related clutch to start the arm swinging when a related key is depressed, one of the triple connections being operable directly by the contacts of the white key and the other two connections being operable by the contacts of one or the other of the adjacent black keys and selected by the pedal operated selecting means through which said two connections pass, triple recording circuit connections from the pairs of contacts over and under a white key and operated by the release thereof for energizing a selected one of the

recording magnets according to the direction of key depression, one of said triple recording connections being operable directly by the contacts of the white key and the other two connections being operable by the contacts of one or the other of the adjacent black keys and selected by the contacts pass, triple restoring circuit connections from the three pairs of contacts over a white key for operating the related restoring means to restore said arm when the key is released, one of said triple restoring connections being operable directly by the contacts of the white key and the other two connections being operable by the contacts of one or the other of the adjacent black keys and selected by the pedal operated selecting means through which said two connections pass, whereby sharp, flat and natural note shapes of different time values can be recorded in the proper positions on said staff lined strip as the corresponding music is played.

22. In a music recording device for recording on a paper strip actual note shapes of whole, half, three-quarter, etc. notes of the entire range and sharp and flat marks associated therewith under control of the keys of a piano, said strip being ruled with a complete set of staff lines extending lengthwise of the strip, pairs of contacts cooperating with each white natural note key, other pairs of sharp and flat control contacts for each natural note key cooperating with adjacent black keys and operated thereby, pairs of contacts for each black key, pedal operated selecting means for making effective either the sharp or flat contacts operated by the black keys, a motor, feeding means cooperating with the paper strip, a train of gearing between said motor and said feeding means, a plurality of sets of recording devices, one set for each natural note key on the piano and comprising sharp, flat, $\frac{1}{16}$ note, $\frac{1}{8}$ note, $\frac{1}{4}$ note, $\frac{1}{2}$ note, $\frac{3}{4}$ note, and whole note recording devices, said recording devices being arranged in the order mentioned in the direction of feed of the strip, magnets for operating the recording devices, dual circuit connections between said black key contacts, the pedal operated selecting means and the sharp and flat recording devices whereby either device is operated momentarily by a key depression, electrical contact sectors, one for each white key, said sectors having individual contact segments connected to the magnets for the $\frac{1}{16}$ note, $\frac{1}{8}$ note, etc., recording devices in the order mentioned, contact arms for said sectors, one arm normally alongside each segment for the $\frac{1}{16}$ note and provided to contact with the segments successively in synchronism with the passage of the record receiving point on the strip under the related recording devices, a magnetic clutch for connecting each arm to the drive gearing, a magnetic restoring means for each arm, triple starting circuit connections from the three pairs of contacts operated by a white key for operating the related clutch to start the arm swinging when a related key is depressed, one of the triple connections being operable directly by the contacts of the white key and the other two connections being operable by the contacts of one or the other of the adjacent black keys and selected by the pedal operated selecting means through which said two connections pass, triple recording circuit connections from the pairs of contacts cooperating with a white key and operated by the release thereof for energizing a se-

lected one of the recording magnets according to the duration of key depression, one of said triple recording connections being operable directly by the contacts of the white key and the other two connections being operable by the contacts of one or the other of the adjacent black keys and selected by the pedal operated selecting means through which said two connections pass, triple restoring circuit connections from the three pairs of contacts cooperating with a white key for operating the related restoring means to restore said arm when the key is released, one of said triple restoring connections being operable directly by the contacts of the white key and the other two connections being operable by the contacts of one or the other of the adjacent black keys and selected by the pedal operated selecting means through which said two connections pass, whereby sharp, flat and natural note shapes of different time values can be recorded in the proper positions on said staff lined strip as the corresponding music is played.

23. In a music recording device for recording on a strip actual note shapes of whole, half, three-quarter, etc. notes of the entire range and sharp and flat marks associated therewith under control of the keys of a piano, said strip being ruled with a complete set of staff lines extending lengthwise of the strip, and measure lines across the strip with intermediate beat lines, said strip having marginal feed perforations with spaced special perforations representing measure length, pairs of controls cooperating with each white natural note key, other pairs of sharp and flat controls for each natural note key cooperating with adjacent black keys and operated thereby, pairs of controls for each black key, manipulative selecting means for making effective either the sharp or flat controls operated by the black keys, a motor, a series of speed changing tempo devices cooperating with said motor, manipulative tempo controls for said speed changing devices, toothed feeding means cooperating with the paper strip, a train of gearing between said motor and said feeding means, a toothed timing means operated by said marginal perforations, sounding devices operated by said timing means to sound beat intervals, a sensing means resting on said strip in alignment with said margin perforations to detect the special measure length perforations, light flashing means and sounding means under control of said sensing means for indicating the appearance of a measure line at the recording position and the passage of a measure length on the strip, a common panel containing said tempo controls and said measure indicating means for placement near the piano, a plurality of sets of recording devices, one set for each natural note key on the piano and comprising sharp, flat, $\frac{1}{8}$ note, $\frac{1}{4}$ note, $\frac{1}{2}$ note, $\frac{3}{4}$ note and whole note recording devices, said recording devices being arranged in the order mentioned in the direction of feed of the strip, connections between said black key contacts, the manipulative selecting means and the sharp and flat recording devices whereby either device is operated momentarily by a key depression, timing selection devices cooperating with said sets of recording devices to select but one device of each set, and means under control of the controls of each white key in cooperation with the timing devices for operating a recording device of the related set according to the duration of key depression, whereby sharp, flat and natural note shapes of dif-

ferent time values can be recorded in the proper vertical and horizontal positions on said staff lined strip as the corresponding music is played.

24. In a music recording device for recording on a strip actual note shapes of whole, half, three-quarter, etc. notes of the entire range under control of the keys of a piano, said strip being ruled with a complete set of staff lines extending lengthwise of the strip, and measure lines across the strip with intermediate beat lines, pairs of contacts cooperating with each note key, a motor, feeding means cooperating with the strip, operating connections between said motor and said feeding means, a plurality of sets of recording devices, one set for each natural note key on the piano and comprising $\frac{1}{8}$ note, $\frac{1}{4}$ note, $\frac{1}{2}$ note, $\frac{3}{4}$ note, and whole note recording devices, said recording devices being arranged in the order mentioned in the direction of feed of the strip, magnets for operating the recording devices, electrical contact sectors, one for each key, said sectors having individual contact segments connected to the magnets for the $\frac{1}{8}$ note, $\frac{1}{4}$ note, $\frac{1}{2}$ note, $\frac{3}{4}$ note and whole note recording devices in the order mentioned, contact arms for said sectors, one arm normally alongside each segment for the $\frac{1}{8}$ note and provided to contact with the segments successively in synchronism with the passage of the record receiving point on the strip under the related recording devices, a magnetic clutch for connecting each arm to the drive connections, a magnetic restoring means for each arm, starting circuit connections from the pair of contacts cooperating with a key for operating the related clutch to start the arm swinging when a related key is depressed, recording circuit connections from the pair of contacts cooperating with a key and operated by the release thereof and through a related segment and contact arm for energizing a selected one of the recording magnets according to the duration of key depression, restoring circuit connections from the pair of contacts cooperating with a key for operating the related restoring means to restore said arm when the key is released, whereby note shapes of different time values can be recorded in the proper positions on said staff lined strip as the corresponding music is played.

25. In a photographic music recording device for picturing on a film strip actual note shapes of whole, half, three-quarter, etc. notes of the entire range and sharp and flat marks associated therewith under control of the keys of a piano, said strip having marginal feed perforations with spaced indicia representing measure length, pairs of contacts under and over each white natural note key, other pairs of sharp and flat control contacts for each natural note key cooperating with adjacent black keys and operated thereby, other pairs of contacts for each black key, manipulative selecting means for closing circuit connections to either the sharp or flat contacts operated by the black keys, a motor, a series of speed changing tempo devices cooperating with said motor, manipulative tempo controls for said speed changing devices, feeding means cooperating with the paper strip, a train of gearing between said motor and said feeding means, a toothed timing means operated by said marginal perforations, sounding devices operated by said timing means to sound beat intervals, a sensing means resting on said strip in alignment with said strip margin to detect the special measure indicia, light flashing means and sounding means under control of said sensing means for indicat-

ing the appearance of a measure line at the recording position and the passage of a measure length on the strip, a common panel containing said tempo controls and said measure indicating means for placement near the piano, a plurality of sets of photographic recording devices with a light source and shutters, one set for each natural note key on the piano and comprising pictures of sharp, flat, $\frac{1}{8}$ note, $\frac{1}{8}$ note, $\frac{1}{4}$ note, $\frac{1}{2}$ note, $\frac{3}{4}$ note, and whole note shapes, said recording devices being arranged in the order mentioned in the direction of feed of the strip, magnets for operating the shutters of the recording devices, dual circuit connections between a pair of said black key contacts, the manipulative selecting means and the magnets of the sharp and flat recording devices whereby the shutter of either device is operated momentarily by a key depression, electrical contact sectors, one for each white key, said sectors having individual contact segments connected to the magnets for the $\frac{1}{8}$ note, $\frac{1}{8}$ note, etc., photographic devices in the order mentioned, a contact arm normally alongside each segment for the $\frac{1}{8}$ note and provided to contact with the segments successively in synchronism with the passage of the photo receiving point on the strip under the related photographic devices, a magnetic clutch for connecting each arm to the drive gearing, a magnetic restoring means for each arm, triple starting circuit connections from the three pairs of contacts under a white key for operating the related clutch to start the arm swinging when a related key is depressed, one of the triple connections being operable directly by the contacts of the white key and the other two connections being operable by the contacts of one or the other of the adjacent black keys and selected by the manipulative selecting means through which said two connections pass, triple recording circuit connections from the pairs of contacts over and under each white key and operated by the release thereof for energizing a selected one of the shutter operating magnets according to the duration of key depression, one of said triple recording connections being operable directly by the contacts of the white key and the other two connections being operable by the contacts of one or the other of the adjacent black keys and selected by the manipulative selecting means through which said two connections pass, triple restoring circuit connections from the three pairs of contacts over a white key for operating the related restoring means to restore said arm when the key is released, one of said triple restoring connections being operable directly by the contacts of the white key and the other two connections being operable by the contacts of one or the other of the adjacent black keys and selected by the manipulative selecting means through which said two connections pass, whereby sharp, flat and natural note shapes of different time values can be photographed in the proper positions on said film as the corresponding music is played.

26. In a music recording device for recording on a strip, sharp and flat marks associated with note recordings under control of the keys of a piano, said strip being ruled with a complete set of staff lines extending lengthwise of the strip, and measure lines across the strip with intermediate beat lines, pairs of sharp and flat control contacts for each natural note white key cooperating with adjacent black keys and operated

thereby, other pairs of contacts for each black key, selecting means for making effective either the sharp or flat contacts operated by the black keys, a motor, feeding means cooperating with the strip, connections between said motor and said feeding means, a plurality of sets of recording devices, one set for each natural note key on the piano and comprising sharp and flat recording devices, magnets for operating the recording devices, dual circuit connections between said black key contacts, said selecting means and the sharp and flat recording devices whereby either device is operated momentarily by a key depression, whereby sharp and flat note shapes can be recorded in the proper positions on said staff lined strip as the corresponding music is played.

27. In a musical control apparatus, an operating instrumentality, a first electrical contact closing device operated by said instrumentality and held closed as long as said instrumentality is operated, a second contact device operated by said instrumentality and closed momentarily at the start of the operation of said instrumentality, and a third contact device operated by said instrumentality and closed momentarily at the end of the operation of said instrumentality.

28. The combination set forth in claim 27, wherein a musical note recording device is controlled to record note shapes on a sheet, a plurality of note recorders for each note value, sharp and flat recorders, a timing device for selecting one of the plural note recorders according to timing of the operating instrumentality, means under control of said first device for controlling said timing device, means under control of said second device for controlling operation of said sharp and flat recorders, and means under control of said third device for stopping said timing device and effecting recording by the selected note recorder.

29. In a music recording device controlled by the operating keys of an instrument, means under control of the keys for recording the natural notes, pairs of sets of flat and sharp notation recorders adjacent certain of the natural note recording means, a plurality of selecting means each of which is associated with one related pair of sharp and flat recorders to make operable one or the other and selected adjacent natural note recording means, and means under control of the keys for operating the operable sharp and flat recorders and the selected natural note recording means.

30. The combination set forth in claim 29, in which said selecting means for sharp and flat recordings are associated in gangs and operable as a unit, and manipulative means for operating said gangs of selecting means to select either sharp or flat notation.

31. In a device for recording musical notation on a note strip under control of a musical instrument with operating instrumentalities, a series of photographic recording means located in alignment in juxtaposition with the sensitized surface of said note strip, means under control of said operating instrumentalities for operating one or more of said photographic means to record on said strip actual note shapes displaced on the strip according to the tone values of the operated instrumentalities, sharp and flat photographic recording means, means under control of the operating instrumentalities for selecting operation of said sharp and flat photographic recording means along with the recording of related

natural note photographic recording means, and means for selecting the recording of either sharp or flat photographic recording means to the exclusion of the other of the two intermediate note photographic recording means.

EDWARD J. CLARK.
